G. A. CUTTING,
GARMENT HANGER,
APPLICATION FILED APR. 19, 1919.

1,334,891.

Patented Mar. 23, 1920.

Inventor:

George A. Cutting

By Mason Tomick Lawrence,

Attorneys

UNITED STATES PATENT OFFICE.

GEORGE A. CUTTING, OF SOUTH PARIS, MAINE.

GARMENT-HANGER.

1,334,891.

Specification of Letters Patent. Patented Mar. 23, 1920.

Application filed April 19, 1919. Serial No. 291,319.

To all whom it may concern:

Be it known that I, GEORGE A. CUTTING, a citizen of the United States, residing at South Paris, in the county of Oxford and 5 State of Maine, have invented certain new and useful Improvements in Garment-Hangers; and I do hereby declare the following to be a full, clear, and exact description of the invention, such as will enable others 10 skilled in the art to which it appertains to make and use the same.

This invention relates to supports and more particularly to clothes supports or other hangers.

15 It is one of the objects of the present invention to provide a simple, practicable, inexpensive and substantial form of device in the nature of a clothes hanger. It is another object of the present invention to provide a clothes hanger which may be readily attached to various convenient supports and also to provide a device of this type which can be easily detached after it has been temporarily, if desired, interengaged with a 25 form of support.

30 A further object of the invention is to provide a clothes hanger a feature of which comprises means of enabling the attachment of the device to a support without to any material degree marring or destroying the 35 surface of the same, so that no marks will be left when the hanger is removed therefrom.

With these and other objects in view as 35 will be rendered manifest to those versed in the art, the invention consists in the construction, the combination, and in details and arrangements of parts as will be explained more fully hereinafter in the following specification relative to the embodiment 40 of the invention illustrated in the accompanying drawings, wherein,

The figure is a perspective view of the hanger illustrated as attached to a portion 45 of a frame.

Preferably the hanger is constructed of a single piece of metal in the form of round wire of suitable length. The wire is bent approximately at its central point between 50 the ends to form an ordinarily shaped garment receiving portion 2, having parallel

straight shanks 3—3 which are twisted together at 4 and thence outwardly in portions 5—5 which are substantially alined. The outer ends of the portions 5—5 are bent 55 upwardly and convergently toward each other as at 6—6 thus forming two oppositely disposed triangular brackets or supporting portions which lie in a common plane. The upper ends of the body portion 6—6 are 60 twisted together as at 7 and the ends of the wires are divergently bent back in horizontal arms 8—8, the terminals of which are bent downwardly as at 9—9 to form penetrating or impaling points 10—10. It will 65 be seen that the hook portion 2 extends forwardly and upwardly from the general plane of the body part consisting of the triangle and the points 10—10 are directed downwardly parallel to the plane of the 70 body part 6—6 and the plane of the points is sufficiently spaced from the plane of the triangle to enable the points to push down behind a strip indicated as at F for instance as a door, window or other frame. In the 75 event that the frame or strip portion F is of greater thickness than the distance of the plane of the points and the body angles 6 then the points can be driven into the top 80 edges of the frame section or arms 8 converged.

From the above it will be seen that I have provided a simple, practicable, inexpensive and easily applied or removed coat or other hanger which can be applied so that the 85 visible surface of the supporting portion will not be materially mutilated.

I claim:

A clothes or other hanger consisting of a single piece of wire having a body part of 90 triangle formation having a horizontal base, the two wires at the apex being intertwined to form a rigid vertical part, horizontal arms extending obliquely back from said rigid vertical part and having downwardly 95 turned impaling points at their extreme tips, and a receiving part bent forwardly from the center of the base of the body part substantially under said rigid vertical part.

In testimony whereof I affix my signature.

GEORGE A. CUTTING.
